UNITED STATES PATENT OFFICE.

NORMAN FREDERICK DAVID BEARD, OF TORONTO, ONTARIO, CANADA.

HOSE-REEL.

1,195,644.

Specification of Letters Patent. Patented Aug. 22, 1916.

Application filed August 6, 1915. Serial No. 44,015.

To all whom it may concern:

Be it known that I, NORMAN FREDERICK DAVID BEARD, a subject of the King of Great Britain, of the city of Toronto, county 5 of York, Province of Ontario, Canada, have invented certain new and useful Improvements in Hose-Reels, of which the following is a specification.

My invention relates to improvements in 10 hose reels, and relates more particularly to improvements in hose reels designed for indoor use, and around which the hose is stored, and the objects of my invention are first, to reduce to a single operation the unreeeling of a hose and the turning on of a full flow of water, so that a stream of water may be more quickly directed to a given point than would be the case were the water valve to be opened by a separate movement; second, where the hose reel is to be supported so as to be swung against a wall, to provide resilient means constantly under tension when the reel is not in use, and held under tension by means which will be destroyed by a rise in temperature, so that the energy stored in said resilient means will be made use of to throw the reel automatically into a position where it is locked so that immediately the hose is unwound therefrom water may be turned on, and third to provide a particular construction of gear for the controlling valve in the conduit supplying the hose with water so that in the type of my reel which is not mounted to be 25 swung horizontally on said conduit, the said controlling valve may be closed without having to immediately rewind the hose for that purpose, and so prevent wastage of water, and the preferred construction of my invention will be hereinafter set forth, and what 30 I claim as new will be pointed out in the claims forming part of this specification.

Figure 1 is a side elevation of my hose reel showing the same coupled to a suitable stand pipe and support. Fig. 2 is a horizontal cross section on the line 2—2 Fig. 1, Fig. 3 is a side elevation of one of the end members of the reel showing the spring mounted thereon whereby energy is stored 45 as the hose is unwound, and Fig. 4 is a central longitudinal section through the valve gear for the controlling valve.

In the drawings like characters of refer-

ence indicate corresponding parts in each figure.

Any suitable type of reel proper may be employed by me in putting my invention into practice, and although I do not show the cross bars therefor as yieldingly mounted to permit of the expansion of the hose as 55 it fills with water, I do not consider this necessary because this feature does not form a part of my invention, and furthermore it is old in the art.

The reel is composed of end members A 65 and B carrying suitable cross bars C around which the hose (not shown) is wound. The end member A is provided with teeth, and is suitably journaled on any suitable coupling support D which is carried by any 70 suitable union E suitably mounted, when required, to turn on the vertical axis of the branch pipe F which is coupled to the stand pipe G.

H is any suitable coupling member rotatably coupled after any suitable manner to the coupling support D.

I is the usual connection to which the end of the hose (not shown) is attached. The end member B is journaled on the stud 2 80 carried by the bracket 3 connected to the coupling 4 carried by the branch pipe F. This coupling may be made to have movement around the branch pipe F when the reel is designed to be swung out of the way 85 against the wall. Coupled to the branch pipe F is any suitable type of valve 5, for instance a gate valve, and this valve controls the passage of water to the coupling member H. The spindle 6 of the valve 5 90 projects beyond one side of this valve, and suitably coupled to said spindle, as by means of the set screw *a* is a hub *b*. Integrally carried by this hub is a spindle *c* on which is feathered the toothed wheel 7.

d is the feather key. *e* is the key-way. The said toothed wheel is retained on the spindle by any suitable means such as a split pin 1. The toothed wheel 7 is normally in contact with the end *r* of the hub 100 *b*, and when the reel is ready for use, this said toothed wheel is in mesh with the teeth of the end member A. When the attendant grasps the nozzle of the hose (not shown), the act of pulling on the hose will cause the 105 reel to rotate, thus consequently rotating

the toothed wheel 7. Through the parts before described, this movement of said toothed wheel is conveyed to the spindle 6, thus opening the valve 5. I calculate that, 5 for example by the time about ten feet of hose have been unreeled, the valve shall have been fully opened.

The face of the toothed wheel 7 is considerably wider than the face of the toothed 10 end member A so that the said toothed wheel will be in mesh long enough with the toothed member A to permit of the full opening of the valve 5. By the time this valve has been fully opened, the toothed 15 wheel 7 shall have been moved out of mesh with the toothed member A, thus allowing as much hose as is desired to be unwound from the reel.

From the foregoing part of this specification it will be understood that by the combination of essential elements set forth, it only requires one movement on the part of the attendant to unreel the hose and turn on the water. This reduction to a minimum 20 of movements is very important. Often-times during excitement, a hose is reeled out to the fire without the water having been turned on. In many cases large fires can be entirely prevented by the saving even of 25 a few seconds of time.

Where my hose reel is mounted to merely rotate and not to be capable of a horizontal swinging movement around its support, some means must be provided to permit the 30 valve 5 to be closed without the necessity of having to turn the reel backward for that purpose, or in other words rewind the hose thereon. After the valve 5 has been fully opened, the toothed wheel 7 is of course 35 automatically moved out of mesh with the toothed member A. Now to independently close the valve 5 without reference to the said reel, the operator grasps the toothed wheel 7 feathered on the spindle c, and operates the same to close the valve. Then 40 he moves the toothed wheel 7 longitudinally on the spindle c into contact with the hub b, during which movement the gearing described is moved into mesh. Allowing for 45 the independent closing of the valve 5 prevents wastage of water through the hose 50 (not shown).

Obviously where my reel is mounted to move horizontally on its support, this horizontal movement will permit of the moving 55 of the toothed member A out of engagement with the toothed wheel 7, and consequently in such case it will not be necessary to feather the toothed wheel 7 on the spindle e.

60 In order to store energy as the hose is being unwound, I provide the coil spring 8, one end of which is suitably secured to the stud 2, and the other end of which is suitably secured to the end member B, for example by means of a pin 9 carried by said

end member. The rotary movement of the reel will result in the winding up of the spring. Particularly in hospitals where there are nurses, fires may occur when none of the men attendants are around. Now 70 where energy can be stored to rewind the hose after it has been used, and made use of in a simple way by those not familiar with mechanical apparatus, a great deal of time and energy is saved, and the chances of 75 making mistakes are reduced to a minimum.

The perimeter of the end member B is provided with ratchet teeth 10, and engaging with these teeth is the pawl 11 mounted on the pin 12 carried by the block 13. Any 80 suitable spring such as the leaf spring 14 mounted on the pin 15 carried by the block 13 may be used to retain the said pawl in operative position. 16 is a stub for said pawl carried by said block. 85

The block 13 is adjustably mounted on the bracket 3 and held in position by the thumb nut 17.

It will be understood that when it is desired to make use of the energy stored in 90 the spring 8, the block 13 will be lowered to remove the pawl out of contact with the teeth 10.

My hose reel may be mounted so as to have movement only on its longitudinal axis, 95 though conditions under which the same may be installed demand that the reel be constructed so as to be swung out of the way against a wall. Now in order that the toothed end member A may be automatically brought into mesh with the toothed wheel 7 as the reel is swung from the dotted position illustrated in Fig. 2 into the position shown in Fig. 1, I provide any suitable 100 means to perform that function. My preferred means comprises a spring 17 which is coupled after any suitable manner as shown at 18 to the stand pipe G and as shown at 19 to the bracket 3. When the reel is swung 105 into the position illustrated in Fig. 2, energy is stored in the spring 17. Suitable means is provided to retain the spring 17 in the position illustrated in Fig. 2, and when this retaining means is released from the spring 17, this spring is strong enough to move the 110 reel into the position illustrated in Fig. 1, thus bringing the toothed member A into mesh with the toothed wheel 7. 115

To lock the reel in the position illustrated in Fig. 1 after the spring 17 has operated, 120 any suitable means may be employed. I show a well-known type of bolt 20 operating through the bracket 21 provided with a coiled spring 22. The end of this bolt extends up into a pocket 23 formed in the coupling member 24, of any suitable construction carried by the union E and mounted to rotate on the branch pipe F. The upper end of this bolt will ride against the flange 25 of the member 24 so as to always be ready 125 130

to shoot into the pocket 23 when this pocket is positioned for that operation. Of course the bolt 20 is retracted from the pocket 23 when it is desired to swing the reel into the 5 position shown in Fig. 2.

In order to reduce to a minimum the chances of mistakes being made during excitement, I provide a coupling means fused by a slight rise in temperature to permit of

- 10 the release of the spring 17 so that the reel may be automatically moved into the position illustrated in Fig. 1. A suitable type of means to retain the spring 17 in the position illustrated in Fig. 2, is as follows: 26 is a link made of material that will readily fuse, and the same is coupled to the end of the spring 17 by the eye 27. Coupled to said link is a split cotter pin 28 which has frictional contact with a pocket 29 formed in
- 15 the coupling 30 which is suitably connected to the wall or other support 31. A sufficient rise in temperature will fuse the link 26, with the result before described.
- 20

Should it be desired to uncouple the 25 spring 17 from the wall or support 31 without destroying the link 26, this can be readily done by exerting sufficient pull to remove the cotter pin 28 from the coupling 30.

From the foregoing specification it will 30 be understood that I have provided a reel which reduces to a minimum the time necessary to direct a stream of water to any given point.

It will of course be understood that it is 35 not absolutely essential for me to make use of the means described for storing energy as the hose is unwound, though I prefer to make use of suitable means for that purpose.

It will also be understood that I do not 40 confine myself to necessarily using the spring 17 and the coupling means therefor in combination with a reel embodying my invention.

While I have described what I consider to 45 be the best embodiment of my invention, I desire it to be understood that the principle can be embodied in different forms and I desire not to be limited beyond the requirements of the prior art and the terms of my 50 claims.

What I claim as my invention is:

1. The combination of a horizontally disposed hose reel having a circular tooth-provided rotary member; a vertically disposed conduit; means coupled to said conduit and on which said reel is mounted to rotate and by means of which water is conveyed to the hose wound on said reel; a horizontally disposed controlling valve in said conduit having its valve rod extending outside the same; a toothed wheel secured to said valve rod and having a face of greater width than the face of said rotary tooth-provided member with which it meshes; the said toothed wheel designed to be operated by said circular
  - 55
  - 60
  - 65
- tooth-provided member to open said controlling valve as the reel is rotated by the pulling of the hose therefrom.
2. The combination with a hose reel having a circular tooth-provided rotary member 70 at its inner end; a conduit; rotatable means coupled to said conduit and on which the inner end of said reel is mounted to rotate, and by means of which water is conveyed to the hose wound on the said reel; a controlling valve in said conduit having its valve rod extending outside the same; a toothed wheel secured to said valve rod and having a face of greater width than the face of said circular tooth-provided member with which it is designed to be brought into mesh; the said toothed wheel designed to be operated by said circular tooth-provided member to open the said controlling valve as the reel is rotated by the pulling of the hose therefrom; a bracket mounted to turn on said conduit and on the upper end of which is journaled the outer end of said reel; a leaf spring attached at its outer end to said bracket, and secured at its inner end to a 80 suitable support, and a fusible link whereby said leaf spring is normally coupled to a wall, the said link designed to be destroyed by a rise in temperature to permit said leaf spring to move said reel to bring said tooth-provided member into mesh with said toothed wheel.
  - 85
  - 90
  - 95
3. The combination with a hose reel having a circular tooth-provided rotary member 100 at its inner end; a conduit; rotatable means coupled to said conduit and on which the inner end of said reel is mounted to rotate, and by means of which water is conveyed to the hose wound on said reel; a controlling valve in said conduit having its valve rod 105 extending outside the same; a toothed wheel secured to said valve rod and having a face of greater width than the face of said circular tooth-provided member with which it is designed to be brought into mesh; the said toothed wheel designed to be operated by said circular tooth-provided member to open the said controlling valve as the wheel is rotated by the pulling of the hose therefrom; a bracket mounted to turn on said 110 conduit and on the upper end of which is journaled the outer end of said reel; a leaf spring attached at its outer end to said bracket, and secured at its inner end to a suitable support, and a fusible link whereby said leaf spring is normally coupled to a wall, the said link designed to be destroyed by a rise in temperature to permit said leaf spring to move said reel to bring said tooth-provided rotary member into mesh with said toothed wheel, and locking means carried by said conduit and designed to engage with said coupling means to lock said reel in 120 operative position in respect of the toothed wheel for said controlling valve.
  - 115
  - 125
  - 130

4. The combination with a hose reel having a circular tooth-provided rotary member at its inner end; a conduit; rotatable means coupled to said conduit and on which 5 the inner end of said reel is mounted to rotate, and by means of which water is conveyed to the hose wound on the said reel; a controlling valve in said conduit having its valve rod extending outside the same; a 10 toothed wheel secured to said valve rod and having a face of greater width than the face of said circular tooth-provided member with which it is designed to be brought into mesh; the said toothed wheel designed to be operated by said circular tooth-provided member to open the said controlling valve as the reel is rotated by the pulling of the hose therefrom; a spring attached at its outer end 15 to the outer end of said reel, and secured at its inner end to a suitable support, and fusible means whereby said spring is normally coupled to a wall, which fusible means is designed to be destroyed by a rise in temperature to permit said spring to move said 20 reel to bring said tooth-provided member into mesh with said toothed wheel.

5. The combination of a horizontally disposed hose reel having a circular tooth-provided rotary member; a vertically disposed conduit; means coupled to said conduit and 30 on which said reel is mounted to rotate and by means of which water is conveyed to the hose wound on said reel; a horizontally disposed controlling valve in said conduit having its valve rod extending outside the same; a toothed wheel feathered on said valve rod, so as to permit of the closing of said valve independently of the movement of said reel; means for limiting the movement of said toothed wheel on said valve rod; the face of 35 said toothed wheel being of greater width than the face of said rotary tooth-provided member with which it meshes in order to open said controlling valve as the reel is rotated by the pulling of the hose therefrom. 40 45

In testimony whereof I do affix my signature in presence of two witnesses.

NORMAN FREDERICK DAVID BEARD.
